UNITED STATES PATENT OFFICE.

KENT W. BARTLETT, OF HAMMOND, INDIANA.

LIQUID-TREATING APPARATUS.

Application filed August 7, 1925. Serial No. 48,781.

My invention relates to liquid treating apparatus and is of particular service when embodied in water softening equipment.

The invention has for its object the provision of improved means, governed by the water or other liquid for supplying chemical to the treatment tank receiving the raw liquid in fixed proportion thereto.

In carrying out my invention in the preferred way, I employ an incoming raw water or raw liquid pipe, discharging into a treatment tank below a limiting level and having an orifice of reduced size in its bore, so that the pressure of the incoming liquid on the receiving side of this orifice is greater than the pressure of the liquid on the discharge side of the orifice. Two receptacles are employed, one connected with the raw liquid pipe upon the receiving side of the reduced orifice in the bore of this pipe and the other connected with this pipe on the discharge side of said orifice. These two receptacles are closed against the admission of external air and air connected by an air passage at their upper portions above the liquid levels therein. The liquid received in one receptacle from the receiving side of the orifice in the raw liquid pipe rises to a higher level than the liquid received in the other receptacle from the discharge side of said orifice. The air passage between the two receptacles enables the liquid in the first receptacle, as it rises, to depress the level of the liquid in the second receptacle, so that the levels in the two receptacles differ in height in proportion to the difference in pressures on the two sides of said orifice. The two bodies of liquid in said receptacles govern valves preferably through the inter-mediation of mechanism having floats riding upon the liquid in said receptacles. The valves controlled by this mechanism are desirably in the form of swinging pipes in a third liquid receiving receptacle. The levels at which the intake ends of these pipes are placed differ in height similarly to the levels in the first two receptacles. One of these swinging pipes discharges into a float tank having a float therein which governs the supply of chemical. The other of these swinging pipes discharges into a fourth receptacle that contains a float that is in controlling relation to a valve that is in a pipe that supplies liquid to the third receptacle, whereby the level to which the liquid may rise in the third receptacle is limited.

The invention will be more fully explained in connection with the accompanying drawing in which Fig. 1 is a view, somewhat diagrammatic, showing the preferred embodiment of the invention, parts being shown in elevation and other parts in section; and Fig. 2 is a sectional view taken generally on line 2-2 of Fig. 1, and under the assumption that the receptacle elements appearing on this line 2-2 are side by side in one unitary structure, as they are in practice.

The invention is described herein as being used for water softening, though it is not to be thus limited.

The treatment or settling tank 1 receives the water or other liquid that is to be treated through the incoming pipe 2, containing a shut off altitude valve 3. An altitude valve serves the purpose of a float valve but is operated by the head of water in the tank instead of by a float. As the head increases the pressure shuts the valve and as the head lowers the pressure decreases and the valve opens. The liquid is discharged into the tank below a limiting level through an orifice 4 smaller than the cross sectional area of the piping 2, the liquid being initially admitted to the tank 1' within the tank 1 and near the top of tank 1'. Tank 1' is closed at the top and discharges, at its bottom, into tank 1. A source of chemical is illustrated in the form of a chemical tank 5, which holds the chemical 6 such as calcium hydrate and sodium carbonate where water is being softened. Chemical, from the source of the chemical, is supplied into the tank 1' through the piping 7 whose discharge end is located near the discharge end of piping 2. The chemical is forced through pipe 7 by means of a pump 8 through which the chemical flows from the swinging pipe 9 mounted in the chemical tank 5, and the continuation 9' of this pipe. The position of this swinging pipe is governed by a float 10 that is connected with the pipe 9 by means of a cable 11 passing over sheave 12. The float tank 13, which contains the float 10, receives a fractional portion of the treated liquid, which is employed to govern the flow of chemical into the treatment tank, through the fixed piping 14, which is flexibly connected with a swinging pipe 15 located in an open receptacle 16. A float 17 is located in a receptacle 18, that is closed

against the admission of air above the liquid therein. The two receptacles 16, 18 are side by side and have a common wall 18' separating them. A shaft 17' is mounted 5 to turn in a bearing 17' which passes through and is carried by the wall 18'. A bent lever 15' is carried by one end of this shaft and extends beneath the pipe 15 to be in lifting relation thereto. The stem 17' of 10 float 17 is fixed upon the other end of the shaft. The float 17, in rising upon elevation of the liquid level in receptacle 18 causes the shaft to turn in a direction to swing lever 15' and, consequently, pipe 15 15 upwardly. When said float descends upon lowering of the liquid level in receptacle 18 the lever 15' is lowered by its own weight and that of the float to permit pipe 15 to descend by its own weight. Receptacle 18 20 has communication through pipe 19 with pipe 2 on the discharge or low pressure side of the orifice 4. Receptacle 18 is connected by the upper air passage 20 with a receptacle 21 that is also closed against the admission of external air above the liquid 25 therein. Receptacle 21 is separated from receptacle 16 by a continuation of wall 18' and in turn is connected by pipe 22 with the inlet pipe 2 on the inlet or high pressure side of orifice 4. A float 23 in receptacle 21 has control of the swinging pipe 24, which is also located in receptacle 16, 30 through mechanism similar to that by which float 17 controls pipe 15. Pipe 24 is flexibly connected through an outer wall of this receptacle with pipe 25, which empties into receptacle 26. Softened water is withdrawn 35 for its intended use through pipe 27 from the upper end of the settling tank 1, a portion flowing from this pipe through piping 28 and to the soft water receptacle 26. The T 9² connects pipe 9' with receptacle 26. Pipe 30 is connected to pipe 29 and supplies 40 soft water to receptacle 16. A float valve 32 is placed in the piping 29, this valve being controlled by the float 32' in turn governed by the level of liquid in receptacle 45 26.

When the apparatus is in operation, water 50 is flowing to the receptacle 26 through piping 29, which also keeps receptacle 16 supplied with softened water.

When no water is flowing through pipe 2, 55 the pressure on both sides of the orifice 4 is the same. Necessarily the pressure in receptacles 18 and 21 is the same so that the water stands at the same level in both receptacles. When the water is flowing into the treatment tank, the pressure of the incoming water before it reaches orifice 4 is greater 60 than on the discharge side of this orifice. This pressure is transmitted to receptacle 21 through pipe 22, and causes the level of the liquid to rise in this receptacle. This increase in water pressure is conveyed through

the air in the closed receptacles 18 and 21 by way of the air passage 20, so as to depress the level of liquid in chamber 18. The difference in the level of the two liquids in chambers 18 and 21 respectively is proportional to the difference in hydrostatic pressures on the two sides of the orifice 4. Float 17 in chamber 18 lowers whereas float 23 in chamber 21 rises. Pipe 24 is used as a means for controlling the level of softened water in the receptacle 16. Valve 33 in pipe 30 is so set as to allow a fixed amount of softened water to enter receptacle 16. This water flows from receptacle 16 through pipes 24 and 25 to receptacle 26 where it mixes with the chemical and water and is pumped back into the treatment tank through pump 8 and pipe 7. The level of liquid in receptacle 16 depends upon the position of pipe 24. Pipes 15 and 24 are always in a relative position to floats 17 and 23, which in turn are governed by the water pressures at the orifice 4. This allows softened water to flow through the orifice in pipe 15 in direct proportion to the amount of water passing the orifice 4 for treatment. When water is not running to the treatment tank, the level of the two liquids in chambers 18 and 21 become the same which raises the intake end 95 of pipe 15 just above the liquid level in receptacle 16 so as to entirely stop any flow to tank 13. When the apparatus is shut down, pump 8 is not operated, all soft water being shut off from receptacle 26 and in turn from receptacle 16.

In the event of excessive flow of chemical diluting water into the tank 26 the float 32' will rise to close the valve 32 to shut off the flow of water through the pipe 29, to prevent further flow of water into the receptacle 26, the flow of water through pipe 30 into the tank 16 being, at the same time, cut off inasmuch as the pipe 30 supplying water to the tank 16 receives its supply from the pipe 29.

Changes may be made without departing from the invention.

Having thus described my invention, I claim:

1. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a source of chemical; and mechanism governing the flow of chemical from the chemical source and inclusive of elements governed by the liquid in said receptacles.

2. In a liquid treating apparatus, the

- combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a source of chemical; and mechanism governing the flow of chemical from the chemical source and inclusive of floats governed by the liquid in said receptacles.

3. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; mechanism controlling said means, the third receptacle supplying liquid to said mechanism which is operable by this liquid; and two mechanisms respectively operated by the liquid bodies in the receptacles that are respectively supplied from the low and high pressure sides of said orifice and respectively governing discharge of liquid from the third receptacle and the admission of liquid to the fourth receptacle.

4. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle.

5. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice and being connected to have the liquid levels therein relatively vary in proportion to the pressures of the liquid on opposite sides of said orifice; a source of chemical; and mechanism governing the flow of

chemical from the chemical source and inclusive of elements governed by the liquid in said receptacles.

7. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice and being connected to have the liquid levels therein relatively vary in proportion to the pressures of the liquid on opposite sides of said orifice; a source of chemical; and mechanism governing the flow of chemical from the chemical source and inclusive of floats governed by the liquid in said receptacles.

8. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being connected to have the liquid levels therein relatively vary in proportion to the pressure of the liquid on opposite sides of said orifice; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; mechanism controlling said means, the third receptacle supplying liquid to said mechanism which is operable by this liquid; and two mechanisms respectively operated by the liquid bodies in the receptacles that are respectively supplied from the low and high pressure sides of said orifice and respectively governing discharge of liquid from the third receptacle and the admission of liquid to the fourth receptacle.

9. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being connected to have the liquid levels therein relatively vary in

proportion to the pressure of the liquid on opposite sides of said orifice; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governed by the liquid in the latter tank and governing said regulating means; and two mechanisms respectively operated by the liquid bodies in the receptacles that are respectively supplied from the low and high pressure sides of said orifice and respectively governing discharge of liquid from the third receptacle and the admission of liquid to the fourth receptacle.

10. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being connected to have the liquid levels therein relatively vary in proportion to the pressures of the liquid on opposite sides of said orifice; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle.

11. In a liquid treating apparatus, the

- combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; mechanism controlling said means, the third receptacle supplying liquid to said mechanism which is operable by this liquid; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation. 5 70 75
12. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation. 10 80 85 90 95 100 105 110 115
13. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being closed against the admission of external air and being connected by an air passage; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation. 120 125 130

connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; mechanism controlling said means, the third receptacle supplying liquid to said mechanism which is operable by this liquid; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation.

15. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being connected to have the liquid levels therein relatively vary in proportion to the pressure of the liquid on opposite sides of said orifices; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation.

20. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being connected to have the liquid levels therein relatively vary in proportion to the pressures of the liquid on opposite sides of said orifice; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation.

25. In a liquid treating apparatus, the combination with a treatment tank receiving liquid to be treated; of a pipe discharging into said tank and having an orifice therein through which the liquid passes and smaller in cross sectional area than the bore of said pipe; two receptacles respectively supplied with liquid from opposite sides of said orifice, said receptacles being connected to have the liquid levels therein relatively vary in proportion to the pressures of the liquid on opposite sides of said orifice; a third receptacle; a fourth receptacle, the third and fourth receptacles having connections to supply them with controlling liquid; a valve controlling the supply of liquid to the third receptacle; mechanism governed by the liquid in the fourth receptacle and operating upon said valve in a closing direction upon increase in the level of this liquid beyond a predetermined point; a source of chemical in communication with the treatment tank to supply chemical thereto; means for regulating the supply of chemical from the chemical source to the treatment tank; a tank supplied with liquid from the third receptacle; mechanism governing said regulating means and inclusive of a float for operating it and which float is actuated by the liquid in the latter tank; and two mechanisms respectively operated by the liquid bodies in the receptacles that are respectively supplied from the low and high pressure sides of said orifice and respectively governing discharge of liquid from the third receptacle and the admission of liquid to the fourth receptacle, each of these two mechanisms being inclusive of a float riding upon said liquid bodies and swinging discharge pipes in the third receptacle with which said floats are in lifting relation.

30. In witness whereof, I hereunto subscribe my name.

KENT W. BARTLETT.
